UNITED STATES PATENT OFFICE.

HERMAN KROSKA, OF POMEROY, IOWA.

COMB CLEANER AND HOLDER.

1,291,028.

Specification of Letters Patent. Patented Jan. 14, 1919.

Application filed February 23, 1918. Serial No. 218,706.

To all whom it may concern:

Be it known that I, HERMAN KROSKA, citizen of the United States of America, and resident of Pomeroy, Calhoun county, Iowa, 5 have invented a new and useful Comb Cleaner and Holder, of which the following is a specification.

The object of this invention is to provide an improved cleaning and holding device 10 for hair combs.

A further object of this invention is to provide improved selective means for mounting a comb cleaner.

My invention consists in the construction, 15 arrangement and combination of elements hereinafter set forth, pointed out in my claims and illustrated by the accompanying drawing, in which—

Figure 1 is a front elevation illustrating 20 my improved comb cleaner and holder mounted on a base. Fig. 2 is a side elevation of the same. Fig. 3 is a front elevation illustrating the cleaner mounted on and carried by a back plate by means of which 25 it may be suspended, the wires of the cleaner being omitted. Figs. 4 and 5 are perspective views of different forms of back plates which may be employed with the device.

In the construction of the device as shown 30 a frame is constructed preferably of wire and comprises spaced side members 10, 11, which are L-shaped in side elevation and connected at their upper and lower ends by cross-bars 12, 13. The entire frame may be 35 integrally formed of a single piece of wire bent to the form described, and may be of any suitable size. A plurality of wires 14 are fixed at their ends to the cross-bars 12, 13 and occupy inclined positions quite close 40 together. The wires 14, which are relatively fine, preferably are twisted to roughen their surfaces, and are here shown exaggerated in diameter and in spacing, for clearness of illustration. A shield 15, formed of a piece 45 of light sheet metal, may be bent around the upper cross-bar 13 and the ends of the wires secured thereto, to cover any rough surfaces or loose ends and provide a smooth finish. Similarly a shield 16 is provided 50 embracing the lower cross-bar 13 and wire ends secured thereto, and one margin of said shield preferably extends a short distance upwardly in contact with end portions of the wires. A scraper 17 is formed of a sepa- 55 rate piece of sheet metal or of the same piece comprising the lower shield 16 and extends

transversely of the lower portion of the frame and is spaced from and substantially parallel with lower portions of the wires 14, the free or scraping margin thereof being directed upwardly toward the upper cross-bar 15. As here shown the shield 16 and scraper 17 are formed of a single rectangular piece of metal of which one margin is fixed to the lower cross-bar 13, the central portion is cut out and folded around in contact with said cross-bar to form the shield 16, and the end and other side marginal portions bent outwardly and then upwardly to form the scraper 17. 70

In use a hair comb may be cleaned by engaging the teeth thereof between the wires 14 and moving the comb back and forth on said wires, thus removing accumulated soil, grease, dandruff and the like from between the teeth. The operation may be completed by drawing the comb over the scraper 17 to remove any foreign matter, extricated from between the teeth by the wires, which may be clinging or adhering to the sides of 80 the comb. 75

Any suitable means may be provided for mounting the cleaner above described, and I have illustrated a number of such means. In Figs. 1 and 2 a base 18 is shown, of any 85 suitable shape, preferably of sheet metal, on which the frame may be mounted. Portions of the base 18 are struck up to form spaced parallel ears 19, 20 adapted to be bent over and embrace base portions of the side frame 90 members 10, 11, by which means the cleaner may be supported in upright position, in any desired location as on a dresser, table, or shelf. 95

In Fig. 3 I have shown the device mounted on a back plate 21 formed of sheet metal of any desired shape and provided with means such as apertures 22 by which it may be suspended from a wall or the like. The back plate is also formed with spaced parallel 100 ears 23, 24 struck out from the body thereof and adapted to be bent over and embrace the upright portions of the L-shaped frame members 10, 11, thus securing the frame and cleaner device to the back plate. 105

In Fig. 4 is shown a form of supporting plate 25 provided with a rearwardly curved integral loop 26 at its upper margin and with spaced parallel ears 27, 28 adapted to engage the upright portions of the L-shaped 110 side members of the cleaner. The plate 25 and device may be suspended as by engag-

ing the loop 26 over the edge of a comb tray or rack or other article of furniture, and an aperture 29 is formed in the bottom of said plate to permit the insertion of a suitable fastening device to assist in holding the device in place.

In Fig. 5 is shown a supporting plate 30 having integral opposed loops 31, 32 at its upper and lower margins adapted to engage racks or bars to hold the device in position, said plate also being formed with ears 33, 34 to engage the upright frame members of the cleaner.

The supporting plates 18, 21, 25 and 30 may be of any desired shapes and suitably finished and ornamented as desired.

The device may be used as a holder for one or more combs by engaging them on the wires in the same manner as for cleaning.

I claim as my invention—

1. A comb cleaner and holder, comprising a frame formed of wire bent to form L-shaped side members connected by upper and lower cross-bars, a plurality of strands of twisted wires connected at their ends to said cross-bars, and a scraping member connected to one of said cross-bars and projecting therefrom in spaced relation to the twisted wires.

2. A comb cleaner and holder, comprising a frame angular in side elevation, a plurality of fine wires connected at their ends to and extending obliquely between the ends of said frame and a scraper fixed to the lower end of said frame and projecting therefrom in spaced relation to the wires.

3. A comb cleaner and holder, comprising a frame including side members formed of

relatively heavy wire, a plurality of relatively fine wires attached at their ends to 40 end portions of said frame, and a supporting plate formed of sheet metal and having ears struck out therefrom and adapted to engage side members of said frame.

4. A comb cleaner and holder, comprising 45 a frame formed of wire bent to form L-shaped side members connected by upper and lower cross-bars, a plurality of fine wires connected at their ends to said cross-bars, and a scraper connected to one of said 50 cross-bars and projecting therefrom in spaced relation to the wires.

5. A comb cleaner and holder, comprising a frame formed of wire bent to form L-shaped side members connected by upper 55 and lower cross-bars, a plurality of fine wires attached at their ends to said cross-bars, and a supporting plate formed of sheet metal and having ears struck out therefrom and adapted to engage side members of said 60 frame.

6. A comb cleaner and holder, comprising a frame formed of wire bent to form L-shaped side members connected by upper and lower cross-bars, a plurality of fine 65 wires attached at their ends to said cross-bars, a scraper secured to said frame adjacent one end portion of the wires, and a supporting plate formed of sheet metal having ears struck out therefrom and adapted to 70 embrace the side members of the frame.

Signed at Pomeroy, in the county of Calhoun and State of Iowa, this 18th day of February, 1918.

HERMAN KROSKA.
